CLAIM

The ornamental design for a pole extension bracket, as shown and described.

DESCRIPTION

FIG. 1 is a top perspective view of a pole extension bracket showing my new design;

FIG. 2 is a top plan view thereof;

FIG. 3 is a side elevational view thereof, the side opposite being substantially a mirror image;

FIG. 4 is a bottom plan view thereof;

FIG. 5 is a left end elevational view thereof; and,

FIG. 6 is a right end elevational view thereof.
